KNOCKDOWN SHEET METAL WINDOW

William H. Klauer, Dubuque, Iowa

Application January 12, 1932. Serial No. 586,222

19 Claims. (Cl. 189—64)

My invention relates to a window construction and has particular reference to windows for use in barns, sheds and similar farm buildings.

The primary object of the invention is to provide a window frame and window which can be formed of sheet metal, which can be manufactured by simple machines and at a low cost, and which can be knocked down and compactly shipped in a small carton, it being necessary for the purchaser to buy only the glass to fit the glass holding frame wherever the window is to be used.

A further object of the invention is to provide a window construction which is easy to put together, which requires only a few common and simple tools, and which can be assembled by an unskilled person.

A further object is to provide a metal window assembly which can be readily mounted in an opening left in the side of a barn or similar building and can be secured in place by the use of nails or screws.

Other objects are to provide a steady and rigid window frame which can be operated very simply, to use certain novel and advantageous connections for the parts of the knock-down frame, and to provide a new arrangement for holding the window shut or in any one of a number of adjusted positions.

These and other objects and advantages of the invention will appear from the following description taken in conjunction with the accompanying drawings which form a part thereof, and will be pointed out in the appended claims.

In the drawings:

Fig. 1 is a perspective view of the assembled window.

Fig. 2 is a perspective view of the parts except the glass holding frame before assembly.

Figs. 3, 4 and 5 are cross sections on the lines 3—3, 4—4, and 5—5 respectively of Fig. 1.

Fig. 6 is a detail view showing the step of assembling the top frame member, one of the side frame members, and one of the angle members.

Fig. 7 is a cross section on the line 7—7 of Fig. 6.

Fig. 8 is a perspective view of the glass holding frame and the glass in position to be assembled.

Fig. 9 is a detail top plan view of a corner of the glass holding frame after assembly.

Fig. 10 is a side elevation of such corner during assembly.

Fig. 11 is a detailed front elevation of the connection between the side and bottom frame members.

Fig. 12 is a side elevation of the same.

Fig. 13 shows the invention assembled and mounted in a building, barn or the like.

Fig. 14 is a detail cross-section on the line 14—14 of Fig. 1.

As shown in Fig. 1, the device may be divided into two parts, the main frame and the glass holding frame. The main frame comprises a top piece 2, a bottom piece 4 and side members 6. Integral with the side members 6 are the cheeks or channel members 8. The main frame is completed by the angle members 10.

The top frame member consists of a main portion 12 arranged substantially in a vertical plane. The bottom edge of the member is bent back upon itself as at 14, the upwardly bent portion being slightly spaced from the portion 12 to leave a groove 16. The portion 14 is then bent outwardly at right angles to the main portion 12 to give a flange 18. The edge of this flange may be made smooth in any way as for instance by turning 75 under the edge portion 20.

At the sides, instead of the flange 18, the portion 14 is rebent into a third plane parallel with the portions 12 and 14, the portion 22 thus formed being likewise spaced slightly from the portion 14 so as to leave a downwardly open groove 23. At the deepest (or uppermost) point of this groove a slot 24 is provided for a purpose to be described below.

The side frame member is shown in cross-section in Fig. 4. The main portion 6 is arranged substantially in the same plane as the top frame member 2. This is bent back upon itself as at 26 and then bent outwardly at right angles to form the cheek or channel member 8 which in turn is closed by a bent flange 28 at the side furthest from the main portion 6. This cheek member is substantially triangular in shape with the apex of the triangle at the bottom, although the bottom is slightly truncated at 29 so that the flange 28 is slightly spaced from the flange 26 even at the bottom of the cheek, forming in fact a trapezoid. The purpose of this space will also be described below.

At the top, and opposite the slots 24, the member 6 carries a lug 30. At the bottom, the portion 26 extends below the cheek 8 and is bent back upon itself as at 32 to form a groove. The deepest part of this groove is provided with a slot 34. In the lower portion of the flange 28 an ear 36 is stamped out so as to extend slightly from the surface of the flange. The upper edge of the cheek member 8 is turned outwardly back upon itself as at 37 to form a downwardly opening groove 39.

The bottom frame member consists of a main portion 4 having on each end a lug 38. The upper edge is bent outwardly or rearwardly to form a flange 40 and is then bent upwardly as at 42 8 at the same angle as the flange 28.

The frame rigidifying angle members 10 have their front edges bent downwardly to form a flange 44. The body portion is substantially in the shape of a right triangle, the hypotenuse 10 being a plain edge. The flange 44 on one of the legs is cut away at an angle from the apex of the right angle as at 46. The other leg has a flange 48 which is bent back upon itself as at 50 to form a hook having an upwardly opening groove 52.

15 The glass holding frame comprises an upper portion 54, side portions 56 and a lower portion 58. Each of these portions is a channel member formed by bending sheet metal to channel shape. The upper portion 54 carries on its rear side a 20 handle 60 to aid in operating the window. Each of the members 54 and 58 carries at its ends lugs 62 while the side members 56 have at their ends slots 64. The channels of the side members are slightly wider than the top and bottom members. 25 These members are all adapted to fit on the edges of the glass 66 when the frame is assembled.

The latching means includes a portion 68 having a downwardly bent part 70 which fits into the groove 16 in the manner shown in Figs. 1 and 30 3. The portion 68 rests on the flange 18. At its outer end a latching member or bar 72 is pivoted thereto. This member carries on its outer end a weight 74 to cause it to hold the window securely. Its lower surface is provided with a 35 plurality of corrugations 76, the corrugation 78 nearest the pivot being somewhat longer than the remaining ones.

The parts of the window are shipped in unassembled condition to the user. In order to assemble 40 the window, the side members 6 are first secured to the bottom frame member 4. The lugs 38 on the end of the bottom frame member are inserted through the slots 34 until the member 4 strikes the bottom of the groove between portions 26 and 32. The lug 38 is then 45 bent over as shown in Figs. 11 and 12 to form the connection. At the same time, the portion 42 slides under the ear 36 to increase the steadiness and rigidity of the joint. The ear 36 may then be bent down tightly against the portion 50. It will be seen that when this arrangement is completed the flange 40 will close the bottom of the truncated pyramid formed by the cheeks 8.

Next, the top frame member 2 is added. The 55 lugs 30 are pressed through the slots 24 and are turned down as shown in Fig. 1. The flange 18 then extends rearwardly beyond the flanges 26.

In order to strengthen the frame and particularly to add rigidity to the cheeks 8, the angle members 10 are used. In order to assemble these, the hook portion 50 is fitted into the groove 39 of the member 8. The angle member is then slid forwardly, while being maintained 60 in an angular position (which is made possible by permitting the hook 50 to fit loosely in the groove 39) as shown in Fig. 6 so that the cut away portion 46 passes above the flange 18. When the angle member reaches the position 70 shown in Fig. 6, it is merely turned downward so that the flange 44 fits in the groove 16 of the top frame member 2. A tight and rigid joint is then provided.

The assembly of the glass holding frame is 75 likewise very simple. The top and bottom mem-

bers 54 and 58 are first placed on the edges of the glass. The side members 56 are then slipped over the side edges of the glass so that the lugs 62 pass through the slot 64 (Fig. 10). The lugs 62 are then bent back upon themselves as shown in Fig. 9 to form a tight frame.

It will be noted that the angle members 10 do not extend all the way to the rear of the cheeks 8. The glass holding frame can therefore be slipped down within the flanges 28 until its bottom member 58 rests on the flange 40. The frame can now be swung backward and upward about its bottom as a fulcrum either to a fully opened position resting on the flanges 28 or to a closed position where it engages the flanges 26.

85 The flange 70 of the portion 68 of the latch member is now placed in the slot 16 (Fig. 3). This is located at the central portion of the window opposite the handle 60. By raising this latch member, the window can be moved so that its frame engages different corrugations in the lower side of the latch 72 so that the window is held at varying angles. When the window is closed, the corrugation 78 engages the handle and pushes the glass holding frame tightly 90 against the flanges 26. This is shown particularly in Fig. 3.

95 It will be seen that it is quite a simple matter to assemble this frame and that it can be done with a hammer and screw driver. When completed, the whole may be placed in any opening provided in a barn or other building as shown in Fig. 13, the portions 2, 4 and 6 being secured to the outer side of the building by nails or the like 100 80. The cheeks 8 then extend within the building and give indirect ventilation, and the flow of air therethrough can be adjusted as desired.

105 While I have described herein one embodiment of my invention, I wish it to be understood that I do not intend to limit myself thereby except within the scope of the appended claims.

110 Having thus described the invention, what I claim as new and desire to secure by Letters Patent of the United States is:

115 1. A knockdown window frame comprising a plurality of parts formed of sheet metal and including side, top and bottom frame members having cooperating means thereon to secure the said parts together substantially in a common plane to form a substantially rectangular frame, a glass holding frame, and means integral with said side frame member to support said glass holding frame.

120 2. A knockdown sheet metal window assembly comprising a main frame having a plurality of flat parts, means on said parts to secure them together substantially in a common plane, said parts including a top portion, a bottom portion and side portions, and a glass holding frame, 125 said bottom portion having means thereon forming a fulcrum for said glass holding frame.

125 3. A knockdown sheet metal window assembly comprising a main frame having a plurality of flat parts, means on said parts to secure them together substantially in a common plane and including a top portion, a bottom portion and side portions, and a glass holding frame, said bottom portion having means thereon forming a fulcrum for said glass holding frame, and said 140 side portions having means thereon to limit the fulcruming movement of said glass holding frame.

145 4. In a sheet metal window frame, a main frame comprising a plurality of parts arranged 150

- substantially in the same plane, some of said parts having grooves therein and slots at the bottoms of said grooves, the other parts having portions with lugs thereon, such portions extending into said grooves and the lugs extending through the slots where they may be bent over to secure the parts together. 5
5. In a knockdown sheet metal window assembly, a frame comprising a plurality of flat parts arranged substantially in a common plane and adapted to be secured to the side of a building, means on said parts for securing said parts to one another, and means extending perpendicularly to said frame to receive a glass holding frame. 10
6. A knockdown sheet metal window assembly comprising a main frame having cheeks extending therefrom and integral therewith, said cheeks being trapezoidal in shape, and a glass holding frame fulcrumed on the shorter base of said trapezoids, said glass holding frame having a thickness less than said shorter base. 15
7. In a knockdown sheet metal window assembly, a frame comprising a plurality of flat parts arranged substantially in a common plane and adapted to be secured to the side of a building, means on said parts for securing said parts to one another, and means extending perpendicularly to said frame to receive a glass holding frame, said receiving means being integral with some of said parts. 20
8. In a knockdown sheet metal window assembly, a main frame including side portions each having main parts lying in a common plane, means to hold said side portions in spaced relation, cheeks integral with said side portions and extending rearwardly perpendicularly to the plane of the main parts thereof, said cheeks being located at a slight distance outwardly from the inner edges of said main parts and parallel to said edges, so as to form a flange on said cheeks, flanges on the rear free edges of said cheeks, a glass holding frame having a width equal to the distance between said cheeks, said cheeks being wider at the top than at the bottom, said flanges being spaced at the bottom by substantially the thickness of said glass holding frame, and means extending between said cheeks to close the space between the bottoms of said flanges, said glass holding frame fulcruming on and being supported by said closing means and being limited in its fulcruming movement by said flanges. 30
9. In a knockdown sheet metal window assembly, a main frame including side portions each having main parts lying in a common plane, means including top and bottom frame members to hold said side portions in spaced relation, cheeks integral with said side portions and extending rearwardly perpendicularly to the plane of the main parts thereof, said cheeks being located at a slight distance outwardly from the inner edges of said main parts and parallel to said edges, so as to form a flange on said cheeks, flanges on the rear free edges of said cheeks, a glass holding frame having a width equal to the distance between said cheeks, said cheeks being wider at the top than at the bottom, said flanges being spaced at the bottom by substantially the thickness of said glass holding frame, and means integral with said bottom frame member extending between said cheeks to close the space between the bottoms of said flanges, said glass holding frame fulcruming on and being supported by said closing means and being limited in its fulcruming movement by said flanges. 40
10. In a knockdown sheet metal window assembly, a main frame including a portion having a groove therein, a second portion secured to said first portion, and means slidable on said second portion and engaging in said groove to fix said portions rigidly. 80
11. In a sheet metal window frame, a pair of frame members arranged substantially in a common plane, one of said members having a portion extending in a plane perpendicular to said first plane, means connecting said members together, and means lying in a third plane perpendicular to both said planes and engaging both said members to fix said members rigidly, said perpendicularly extending portion on one member and the other member having grooves therein, said last means having portions engaging in said grooves, and being oscillatable with respect to said extending portion by an amount sufficient to permit the engaging portion to enter the groove in the other member. 85
12. In a knockdown sheet metal window assembly, a main frame including a frame member having a groove therein parallel to one edge thereof, a second frame member arranged substantially in the same plane as said first frame member and secured thereto and having a portion extending in a direction substantially perpendicular to said groove, said second frame member having a portion extending substantially perpendicularly to said plane and having its upper edge substantially perpendicular to said groove, said upper edge being turned over to form a second groove opening in the opposite direction from said first groove, and a frame rigidifying member disposed substantially perpendicularly to said plane and to said perpendicularly extending portion, said rigidifying member having one edge turned over to form a hook engaged in said second groove and having a second edge perpendicular to and adjacent said first edge turned down to form a flange extending into said first groove, whereby a rigid joint is formed. 90
13. In a knockdown sheet metal window assembly, a main frame including a frame member having a groove therein parallel to one edge thereof, a second frame member arranged substantially in the same plane as said first frame member and secured thereto and having a portion extending in a direction substantially perpendicular to said groove, said second frame member having a portion extending substantially perpendicularly to said plane and having its upper edge substantially perpendicular to said groove, said upper edge being turned over to form a second groove opening in the opposite direction from said first groove, and a frame rigidifying member adapted to be disposed substantially perpendicularly to said plane and to said perpendicularly extending portion, said rigidifying member having one edge turned over to form a hook loosely and slidably engageable in said second groove and having a second edge perpendicular to and adjacent said first edge turned down to form a flange, the portion of said flange adjacent said first edge being cut away, whereby said rigidifying member may be slid onto said perpendicularly extending portion slightly out of the perpendicular thereto until said flange is aligned with said first groove and may then be turned to a perpendicular position whereby the flange engages in said groove and makes a rigid joint. 100
14. In a knockdown sheet metal window frame, a main frame including a top frame member comprising a main plane portion having a hori- 105

zontal groove, a glass holding frame fulcrumed on said main frame near the bottom thereof, and means engaging in said groove and supported thereby to hold the top of said glass holding frame in a plurality of adjusted positions.

- 5 15. In a knockdown sheet metal window frame, a main frame including a top frame member comprising a main plane portion having a horizontal groove, a glass holding frame fulcrumed on said main frame near the bottom thereof, and means engaging in said groove and supported thereby to hold the top of said glass holding frame in a plurality of adjusted positions, said holding means including an angle member having a leg extending into said groove and a bar pivoted to said angle member and having corrugations in the lower side thereof adapted to engage the upper edge of said glass holding frame.
- 10 16. In a knockdown sheet metal window frame, a main frame including a top frame member comprising a main plane portion having a horizontal groove, a glass holding frame fulcrumed on said main frame near the bottom thereof, and means engaging in said groove and supported thereby to hold the top of said glass holding frame in a plurality of adjusted positions, said holding means including a bar having corrugations in the lower side thereof adapted to engage the upper edge of said glass holding frame, and a handle on the rear side of the upper part of said glass holding frame, the corrugation nearest the top frame member being adapted to engage said handle from the rear to push the frame tightly into closed position, said last corrugation extending downwardly further than the other corrugations on said bar.
- 15 17. In a knockdown sheet metal window assembly, a main frame including a top frame member comprising a main plane portion having a horizontal groove, a glass holding frame fulcrumed on said main frame near the bottom thereof, and means engaging in said groove and supported thereby to hold the top of said glass holding frame in a plurality of adjusted positions, said holding means including a bar having corrugations in the lower side thereof adapted to engage the upper edge of said glass holding frame, and a handle on the rear side of the upper part of said glass holding frame, the corrugation nearest the top frame member being adapted to engage said handle from the rear to push the frame tightly into closed position, said last corrugation extending downwardly further than the other corrugations on said bar.
- 20 18. In a knockdown sheet metal window assembly, a main frame including a top frame member comprising a main plane portion having a horizontal groove, a glass holding frame fulcrumed on said main frame near the bottom thereof, and means engaging in said groove and supported thereby to hold the top of said glass holding frame in a plurality of adjusted positions, said holding means including a bar having corrugations in the lower side thereof adapted to engage the upper edge of said glass holding frame, and a handle on the rear side of the upper part of said glass holding frame, the corrugation nearest the top frame member being adapted to engage said handle from the rear to push the frame tightly into closed position, said last corrugation extending downwardly further than the other corrugations on said bar.
- 25 19. In a knockdown sheet metal window assembly, a main frame including a top frame member comprising a main plane portion having a horizontal groove, a glass holding frame fulcrumed on said main frame near the bottom thereof, and means engaging in said groove and supported thereby to hold the top of said glass holding frame in a plurality of adjusted positions, said holding means including a bar having corrugations in the lower side thereof adapted to engage the upper edge of said glass holding frame, and a handle on the rear side of the upper part of said glass holding frame, the corrugation nearest the top frame member being adapted to engage said handle from the rear to push the frame tightly into closed position, said last corrugation extending downwardly further than the other corrugations on said bar.
- 30 20. In a knockdown sheet metal window assembly, a main frame including a top frame member comprising a main plane portion having a horizontal groove, a glass holding frame fulcrumed on said main frame near the bottom thereof, and means engaging in said groove and supported thereby to hold the top of said glass holding frame in a plurality of adjusted positions, said holding means including a bar having corrugations in the lower side thereof adapted to engage the upper edge of said glass holding frame, and a handle on the rear side of the upper part of said glass holding frame, the corrugation nearest the top frame member being adapted to engage said handle from the rear to push the frame tightly into closed position, said last corrugation extending downwardly further than the other corrugations on said bar.
- 35 21. In a knockdown sheet metal window assembly, a main frame including a top frame member comprising a main plane portion having a horizontal groove, a glass holding frame fulcrumed on said main frame near the bottom thereof, and means engaging in said groove and supported thereby to hold the top of said glass holding frame in a plurality of adjusted positions, said holding means including a bar having corrugations in the lower side thereof adapted to engage the upper edge of said glass holding frame, and a handle on the rear side of the upper part of said glass holding frame, the corrugation nearest the top frame member being adapted to engage said handle from the rear to push the frame tightly into closed position, said last corrugation extending downwardly further than the other corrugations on said bar.

40

zontal groove, a side frame portion having a main part substantially in the same plane as said top frame main portion and a cheek extending substantially at right angles to said plane and forming a part of a means to receive a glass holding frame, and a member slidable on said cheek and having a flange engageable in said groove to lock it against sliding movement, and means mounted in said groove to engage the upper edge of a glass holding frame to hold the same in a plurality of adjusted positions.

80 22. In a knockdown sheet metal window assembly, a main frame including side portions each having flat main parts lying in a common plane, means to hold said side portions in spaced relation, cheeks integral with said side portions and extending rearwardly perpendicularly to the plane of the main parts thereof, said cheeks being located at a slight distance outwardly from the inner edges of said main parts and parallel to said edges, and flanges on the rear free edges of said cheeks, said cheeks serving to hold a glass holding frame.

90 23. In a knockdown sheet metal window assembly, a main frame including side portions each having flat main parts lying in a common plane, means including flat top and bottom members arranged in said plane to hold said side portions in spaced relation, means on said side portions and flat members to hold them together, cheeks integral with said side portions and extending rearwardly perpendicularly to the plane of the main parts thereof, said cheeks being located at a slight distance outwardly from the inner edges of said main parts and parallel to said edges, and flanges on the rear free edges of said cheeks, said cheeks and flanges serving to hold a glass holding frame.
